Related U.S. Application Data

(62) Division of application No. 29/702,611, filed on Aug. 20, 2019, now Pat. No. Des. 929,268.

Primary Examiner — Darlington Ly(74) *Attorney, Agent, or Firm* — Foley & Lardner LLP(51) **LOC (14) Cl.** ..... 12-11**CLAIM**(52) **U.S. Cl.**

We claim the ornamental design for a bicycle, as shown and described.

USPC ..... **D12/111****DESCRIPTION****(58) Field of Classification Search**

USPC D12/111, 117; D21/412, 414, 419, D21/423–428, 431–435

CPC B62K 3/00; B62K 3/02; B62K 3/06
See application file for complete search history.**(56) References Cited**

FIG. 1 is a top, front, and right side perspective view of a bicycle embodying our new design;

U.S. PATENT DOCUMENTS

FIG. 2 is a top, rear, and left side perspective view thereof;

5,197,795 A	3/1993	Mudrovich
6,016,882 A	1/2000	Ishikawa
6,029,990 A	2/2000	Busby
6,095,270 A	8/2000	Ishikawa
6,148,944 A	11/2000	Adomi et al.
6,155,585 A	12/2000	Busby
6,276,479 B1	8/2001	Suzuki et al.

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the drawing illustrate portions of the bicycle that form no part of the claimed design.
